UNITED STATES PATENT OFFICE

2,017,285

REFRIGERATOR

Carl E. L. Lipman, Chicago, Ill., assignor to Lipman Patents Corporation, Chicago, Ill., a corporation of Delaware

Application July 18, 1932, Serial No. 623,077

10 Claims. (Cl. 62—116)

This invention relates to mechanically operated refrigerators and more particularly to refrigerators especially suitable as water coolers although it will be manifest that the invention is not limited to this particular type of refrigerator.

Two of the principal problems encountered in mechanical refrigeration are the provision of proper insulation and the service, repair or replacement of the refrigerating unit. The latter is particularly important where hermetically sealed units are employed.

It is one of the purposes of this invention therefore to provide a refrigerator comprising a cabinet having suitable insulated cabinet space for either or both cooling water and storing articles, and a mechanically operated refrigerating unit therefor which is constructed and arranged in combination with the cabinet in such a manner that the refrigerating unit may be removed from the cabinet as a unitary structure to permit service, repair or replacement.

In accordance with this invention the cabinet is constructed with a removable wall which is utilized as the carrier for the entire unit and which is preferably supported in such a manner that the wall and unit may be moved and latched into position with a minimum amount of effort and mechanism.

30 A better understanding of this invention will be had from the following description considered in connection with the drawings which illustrate one embodiment of this invention and in which:

Fig. 1 is a front elevation of a water cooler embodying the construction of this invention.

Fig. 2 is a transverse vertical section through approximately the center of the water cooler.

Fig. 3 is a side elevation of the refrigerating unit removed from the cabinet.

40 Fig. 4 is a side elevation partly in section of the cabinet with the refrigerating unit removed.

Fig. 5 is a transverse horizontal section on line 5—5 of Fig. 1.

Fig. 6 is a transverse horizontal section on line 45 6—6 of Fig. 1.

Fig. 7 is a transverse horizontal section on line 7—7 of Fig. 1.

Fig. 8 is a transverse horizontal section on line 8—8 of Fig. 1.

50 Referring to the drawings, which merely illustrate one practical embodiment of this invention in the form of a water cooler, it will be seen that the refrigerator shown embodies a cabinet 1 having an insulated upper portion which includes a storage compartment 2 and a water cooling com-

partment 3, both compartments being surrounded by insulation and separated by a partition 4. Beneath the compartments 2 and 3 is the apparatus compartment 6 which houses the refrigerant circulating apparatus later to be described. The top of the cabinet is closed by a top 7 provided with an opening 8 surrounded by a rubber bushing 9 to receive the neck of a water vessel 10 in the usual manner. The vessel discharges its contents into a receptacle 11 which may be 10 drained by the usual connection 12 and which is in thermal conductive relation to a cooling element comprising a boiler or evaporator 13 disposed immediately below and partly surrounded by the receptacle 11. The cooling element also 15 serves to cool the storage compartment 2.

The evaporator is supplied with a refrigerant from a refrigerant circulating apparatus 14 comprising in this instance a motor compressor unit 16, the refrigerant being conducted and returned 20 by pipes 17 and 18 respectively. The temperature of the cooler may be maintained at any desired degree by the usual thermostatic element 19 and controller 21, the latter being connected in the electrical circuit to the motor compressor 25 unit. The current is supplied to the motor compressor unit by the usual cord 22.

One of the walls of the cabinet, in the present illustration the front wall 25, is removable substantially in its entirety and is utilized as the 30 supporting and carrying medium for the entire refrigerating unit, i. e. the cooling element and the refrigerant circulating apparatus. This wall is also provided with a door 26 which leads into the storage compartment 2 and has a removable 35 louvered panel 27 below door 26 and permits access to the apparatus compartment. The louvered panel is removable to permit access to the securing latch as will be later described and also permits entry of cooling air into the apparatus 40 compartment. The air entering the louvers flows over the motor compressor unit and outwardly through the rear of the compartment into a duct 28 which extends upwardly along the back of the cabinet and discharges at the upper end thereof. 45

Adjacent the upper end of the wall the cooling element or evaporator is secured to the inner surface thereof and projects inwardly therefrom. Adjacent its lower end the wall is provided with a support or bracket 29 which projects laterally 50 therefrom into the cabinet when the wall is in position. The support 29 constitutes a base for the refrigerating apparatus including the motor compressor unit 16 and associated parts.

A pair of rollers 31 is secured to the lower end 55

of the removable wall to facilitate its removal from and replacement into the cabinet. Adjacent the inner end of the support 29 the latter is also provided with a single centrally disposed roller 32, 5 the periphery of which is higher than the periphery of rollers 31 when the wall is vertical, that is, the periphery of roller 32 does not lie within the plane perpendicular to and passing through the lower edge of wall 25.

10 The foregoing arrangement of rollers 31 and 32 will cause the wall to tilt slightly to the right as shown in Fig. 3 when the wall and the refrigerating unit are removed from the cabinet. When being replaced into the cabinet the wall 15 and refrigerating unit carried thereby may be rolled into the cabinet upon the rollers 31 and 32 until almost in position at which time the top end of the wall 25 engages the top end 34 of the wall opening and at which time the upper end of the 20 wall will be practically in position. The lower end will project outwardly and upon further movement of the wall toward and into the cabinet the wall will pivot about its upper end whereby roll 32 will leave the floor as shown in Figs. 1 and 2, just 25 as the lower end of the removable wall assumes its closed position. The wall may be securely latched in place through the medium of an apertured spring bar 36 having an aperture 37 adjacent its outer end and in position to engage a 30 keeper 38 secured to the wall.

When in position the weight of the refrigerating unit tends to maintain the upper end of the wall in tight engagement with the cabinet whereas the latch holds the lower end securely in position. In one aspect the wall may then be said to pivot about the latch by the effect of gravity and maintain itself in closed position. In order to remove the wall it is merely necessary to remove the louvered panel 27, disengage spring bar 36, 40 allow the lower end of the wall to swing downwardly until all three rollers 31 and 32 engage the floor and then roll the wall with the refrigerating unit thereon to any desired location.

45 The wall may also be conveniently utilized to carry the drip pan or tray 41, if desired.

In order that the motor compressor unit may be removed without disturbing the wiring connections, a detachable plug 42 (Fig. 8) is provided 50 which permits a severing of the electrical connections without necessitating disconnecting any wires.

It follows from the above disclosure that a refrigerator has been provided in which the cabinet 55 construction and refrigerating unit is so combined that the latter conveniently may be removed from the cabinet for service repair or replacement without the necessity of disconnecting any pipes or lateral connections and that the 60 cabinet is so arranged as to give ample provision for cooling space as well as storage space.

It is obvious that the principles of my invention may be incorporated into other refrigerators than water coolers and that various changes may 65 be made in the details of construction without departing from the spirit and scope of this invention as defined in the claims.

I claim:

1. In combination a refrigerator cabinet having 70 a plurality of compartments therein closed upon one side by a removable wall having a door therein leading to one of said compartments, said wall being detachable in its entirety from the cabinet, means for securing said wall in position, and 75 a refrigerating unit carried by said wall and re-

movable therewith said unit comprising a cooling element carried by said wall in position to be disposed in one of said compartments and a refrigerant circulating apparatus for supplying said element with refrigerant carried by said wall in 5 position to be disposed within another of said compartments.

2. In combination a refrigerator cabinet having 10 a removable wall one end of which pivotally engages with the cabinet, a roller upon the opposite end whereby the wall may be engaged at one end and rolled into position, means for latching the latter end in position, and a refrigerating unit secured to said removable wall and projecting into the cabinet, said unit being removable 15 with said wall.

3. In combination a refrigerator cabinet having 20 a removable wall one end of which pivotally engages with the cabinet, means for latching the opposite end in position, said removable wall 25 being constructed and arranged so that gravity tends to maintain the latter end away from the cabinet when unlatched, and a refrigerating unit secured to said removable wall and projecting into the cabinet, said unit being removable with said wall.

4. In combination a refrigerator cabinet having 30 a removable wall, rollers for supporting said wall and arranged thereunder with respect to the center of gravity of said wall so that said wall 35 will assume an angle less than ninety degrees (90°) with respect to the floor when said wall is removed from the cabinet, means for securing said wall in position, and a refrigerating apparatus carried by and removable with said wall. 35

5. The combination of a refrigerator cabinet having 40 a removable wall and a support projecting laterally therefrom into said cabinet and means for securing said wall in position, with a refrigerating apparatus carried by said support and removable with said wall, said support and apparatus being so arranged that gravity tends to hold the upper end of said removable wall in contact with said cabinet when the wall 45 is in position.

6. In combination, a refrigerator cabinet having 50 a removable wall, a support projecting laterally from the lower end of said wall into said cabinet, a roller beneath the lower end of said wall and a roller beneath said support, said latter roller being in a plane above a plane perpendicular to the wall and passing through the lower end thereof.

7. A refrigerating structure including a cabinet 55 providing a heat insulated compartment and an apparatus compartment, a heat absorbing element mounted on the inner face of the front wall of the cabinet in position to be disposed within the heat insulated compartment, a door carried by said wall, a bracket secured to the inner 60 face of said front wall in position to be disposed within said apparatus compartment, heat dissipating apparatus carried by said bracket, refrigerant circulating connections extending within the cabinet between said apparatus and 65 said element, said front wall together with said element, said bracket, said apparatus and said connections being removable as a unit from the cabinet, and means for detachably locking said unit in cooperative relation with said cabinet to 70 close the front side of both of said compartments.

8. A refrigerating structure comprising a cabinet 75 providing a heat insulated compartment and an apparatus compartment, both of said com-

- 5 compartments being open at the front, a unit comprising a wall structure adapted to close the front of both of said compartments and having provision for access therethrough to said insulated compartment, a heat absorbing element and a refrigerating apparatus carried by said wall structure in position to be inserted respectively into said insulated and apparatus compartments and connections extending along the inner face of said wall structure through which circulation of refrigerant between said apparatus and said element may be effected, and means for detachably locking said wall structure to said cabinet structure.

10 9. A refrigerating structure including a cabinet providing a heat insulated compartment and an apparatus compartment both open at the front side, a unit comprising a wall structure, a heat absorbing element, a heat dissipating apparatus and connections between said element and apparatus, said element, apparatus and connections being all mounted on the wall structure and said wall structure being adapted to close the open side of both of said compartments, and means for securing said wall structure in cooperative relation with said cabinet, said apparatus

15 10. A refrigerating structure comprising a cabinet providing a heat insulated compartment and an apparatus compartment both of said compartments being open at the front side, a wall structure adapted to close of said compartments and constructed to permit access there through to the insulated compartment, means for securing said wall structure in cooperative closing relation with said cabinet, a refrigerating unit including a heat absorbing element and a heat dissipating apparatus carried by said wall structure in position to be disposed within said heat insulated compartment and said apparatus compartment respectively, said wall structure and refrigerating unit being separable as a unit from said cabinet, said unit being so mounted on the wall structure as, in conjunction with said securing means, to effect a sealing relation between the wall structure and the walls of the heat insulated compartment.
